UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A MIRROR-BACK.

SPECIFICATION forming part of Design No. 26,458, dated December 29, 1896.

Application filed September 23, 1896. Serial No. 606,795. Term of patent 7 years.

To all whom it may concern:

Be it known that I, WILLIAM C. CODMAN, a subject of the Queen of Great Britain, residing at Providence, in the county of Providence and State of Rhode Island, have invented and produced a new and original Design for Mirrors, of which the following is a specification, reference being had to the accompanying drawing, forming part thereof.

10 The drawing is a view of a back of a mirror, showing my design.

The leading feature of my design consists in a border of raised scrolls having floral designs interspersed with the scrolls and inclosing the plain surface of the central blank space of the circular back.

15 In the drawing, A indicates the circular outline or edge of the mirror-back. This edge is rounded, as shown by the shading in the drawing.

B is a raised ornamental border; C, the central flat space.

20 Some of these mirrors are made without handles, some with a loop D, (shown in the

25 drawing in solid lines,) which serves as a short handle and a loop by which the mirror can be suspended, and some of the mirrors are provided with a longer handle E. (Indicated in broken lines in the drawing.) The ornamental border B extends around the mirror-back along the convex edge. It consists of the foliated scrolls f/f, alternately curved inward and outward, and the four floral groups g g g g, representing open roses with buds and leaves. The ornamental border B 30 is raised above the surface C of the back, forming a repoussé ornamental border.

35 Having thus described my newly-produced design, I claim as new and desire to secure by Letters Patent—

40 The design for the back of a mirror or similar article herein shown and described.

In witness whereof I have hereunto set my hand.

WILLIAM C. CODMAN.
